CLAMP

Application filed April 9, 1929. Serial No. 353,834.

This invention relates to a clamp and has for its object to provide a device which may be employed for the purpose of securing a portion of a mold for concrete to a structural member which is to be enclosed within the concrete and at the same time space the mold member a predetermined distance from the structural member.

The invention consists in a clamp for a concrete mold structure as set forth in the following specification and particularly as pointed out in the claims thereof.

Referring to the drawings:

Figure 1 represents a sectional elevation illustrating the lower portion of an I-beam, a bottom member of a mold for concrete, and a pair of clamps embodying our invention, said clamps being secured in position upon the bottom flange of the I-beam and supporting and spacing the bottom member of the mold upon the I-beam.

Fig. 2 is a side elevation of the clamp, together with portions of the I-beam and bottom member of the mold.

Fig. 3 is a plan view of the clamp and portion of the flange of the I-beam to which it is secured.

Like numerals refer to like parts throughout the several views of the drawings.

In the drawings, A represents a flanged structural member, preferably an I-beam of well known form and having the usual flanges *a* upon opposite sides thereof. B represents a board or panel constituting the bottom member of a mold for concrete which is desired to have spaced a predetermined distance beneath the under surface of the structural member A.

The device of this invention consists of a clamp 5 which is utilized to secure the mold member B to the structural member A and at the same time space said members the required distance apart. The clamp 5 embodies therein a tubular spacing member 6 which is split upon opposite sides thereof at 7 to enable a portion of the tubular member to be bent laterally to form a gripping jaw 8. Upon the opposite side of the tubular member from the gripping jaw 8 the tubular member is flared outwardly a short distance

at 9 and a rectangular hole 10 is provided therein. Mounted upon the tubular member 6 is a gripping jaw 11, which is preferably formed of a flat bar of iron or steel, the gripping portion of which is bent at a suitable angle to engage the inclined surface of the flange *a* of the structural member A.

The gripping jaw 11 is shouldered to form a tongue portion 12 which is adapted to be inserted within the hole 10 of the tubular member 6. The tongue 12 is, furthermore, formed in such a manner that it is necessary to tip the gripping jaw 11 in order to insert said tongue within the hole 10 and the outer end portion of the tongue flares outwardly at 13 so that the gripping jaw 11 cannot be pulled through the hole 10 without its first being tipped into a position approximately at right angles to its normal position.

A bolt 14 extends through a hole 15 provided therefor in the mold member B and upwardly through the tubular spacing member 6 and through a hole 16 provided in the gripping jaw 11, and said bolt is utilized to simultaneously clamp the mold member B to the tubular member 6 and the latter to the flange *a* of the structural member A by tightening the gripping member 11 against the upper surface of the flange *a* and securely gripping said flange between the stationary gripping jaw 8 and the movable gripping member 11.

As many of the clamps 5 may be employed as may be desired in securing the mold member B to the structural member A, and the holes 15 are preferably so located in the mold member B that the bolts 14 will engage the edges of the flange *a* and thereby correctly position the mold member B upon the structural member.

It will be understood that suitable side members (not shown in the drawings) are provided for the mold and secured in position in a manner well known to those skilled in the art before the concrete is poured. After the concrete is set, to remove the mold member B, the bolts 15 are unscrewed from their respective nuts and withdrawn, leaving the remainder of the clamp embedded in the concrete.

We claim:

1. A clamp of the character described having, in combination, a tubular spacing member, a fixed jaw portion projecting laterally therefrom, a jaw pivotally mounted upon the tubular member, and means within the passage of the tubular member to actuate the pivoted jaw to move the same relatively to the fixed jaw.

10 2. A clamp of the character described having, in combination, a tubular spacing member provided with a laterally projecting fixed jaw portion formed integral therewith, a jaw pivotally mounted upon the tubular member, and means within the passage of the tubular member to actuate the pivoted jaw to move the same relatively to the fixed jaw.

20 3. A clamp of the character described having, in combination, a tubular spacing member provided with a laterally projecting fixed jaw portion formed integral therewith and also having an opening provided therein, a movable jaw provided with a tongue 25 projecting through said opening and interlocking with the spacing member, and means within the passage of the tubular member to actuate the movable jaw to move the same relatively to the fixed jaw.

30 4. A clamp of the character described having, in combination, a tubular spacing member provided with a laterally projecting fixed jaw portion formed integral therewith and also having an opening provided therein, a movable jaw provided with a tongue 35 projecting through said opening and interlocking with the spacing member, and a bolt extending through the tubular member and engaging the movable jaw whereby the latter is rocked upon the tubular member.

40 5. In combination, a structural member, a mold member, a tubular member between the structural and mold members and spacing said members apart, a gripping jaw 45 pivotally attached to the tubular member, and means to simultaneously clamp the mold member to the spacing member and actuate the gripping jaw to clamp the spacing member to the structural member.

50 6. In combination, a structural member, a mold member, a tubular member between the structural and mold members and spacing said members apart, a fixed jaw portion projecting laterally from the tubular member, a gripping jaw pivotally mounted upon the tubular member, and means to simultaneously clamp the mold member to the spacing member and actuate the pivoted gripping jaw to clamp the spacing member 55 to the structural member.

60 7. In combination, a structural member, a mold member, a tubular member between the structural and mold members and spacing said members apart, a fixed jaw portion 65 projecting laterally from the tubular mem-

ber, a gripping jaw pivotally mounted upon the tubular member, and a bolt extending through the tubular member and engaging the pivoted gripping jaw whereby the structural member is clamped between both of the gripping jaws.

In testimony whereof we have hereunto set our hands.

ABRAHAM E. SHLAGER.
LOUIS SHLAGER.
BENNETT M. GROISER.
